[57] CLAIM

The ornamental design for a modular electrical plug, as
shown and described.

DESCRIPTION

FIG. 1 is a top plan view of the modular electrical plug
showing our new design;

FIG. 2 is a right side elevational view thereof, the left
side being a mirror image thereof;

FIG. 3 is a front elevational view thereof;

FIG. 4 is a rear elevational view thereof;

FIG. 5 is a bottom plan view thereof; and

FIG. 6 is a bottom, rear perspective view thereof.

FIG. 1

FIG. 3

FIG. 2

FIG. 4

FIG. 5

FIG. 6
